REFRIGERATING APPARATUS

Filed May 28, 1930

UNITED STATES PATENT OFFICE

OTTO M. SUMMERS, OF DAYTON, OHIO, ASSIGNOR TO FRIGIDAIRE CORPORATION, OF DAYTON, OHIO, A CORPORATION OF DELAWARE

REFRIGERATING APPARATUS

Application filed May 28, 1930. Serial No. 456,735.

This invention relates to evaporators for refrigerating apparatus and more particularly to the refrigerant control mechanism for such evaporators.

One of the objects of this invention is to provide an improved refrigerant control mechanism for an evaporator for a refrigerating apparatus, which control mechanism includes a valve, and to arrange said mechanism in such a manner so as to prevent damage to said valve or its seat in the event said evaporator is subjected to abnormal conditions.

More specifically it is an object to prevent the aforesaid valve from jamming its seat during transportation of said evaporator.

Further objects and advantages of the present invention will be apparent from the following description, reference being had to the accompanying drawings, wherein a preferred form of the present invention is clearly shown.

In the drawings:

Fig. 1 is a view illustrating diagrammatically a refrigerating system including the evaporator, on a larger scale, embodying features of the present invention, said evaporator being shown in cross section, and

Fig. 2 is a fragmentary view of a portion of the evaporator shown in Fig. 1, the view being taken in the direction of the arrows 2-2.

Referring to the drawings, the numeral 20 designates in general an evaporator, comprising a header or container 21 forming a reservoir for liquid refrigerant, such as sulphur dioxide, and from which header depends a plurality of refrigerant conveying ducts 22 for conveying the refrigerant to the zone or place to be refrigerated. Refrigerant is delivered to the header through refrigerant conveying pipe 24 and is withdrawn through a vapor pipe 25. The pipe 24 is connected with a receiver 27 and the pipe 25 is connected to the low pressure side of a compressor 30, preferably as shown to the crank case thereof. The high pressure side of the compressor is connected with a condenser 31 which in turn is connected with the receiver 27. The compressor is herein shown as driven by a motor 33 which is controlled in

response to the pressure within the pipe 25 by means of an automatic switch 34 which connects the motor with the power mains 35.

The header 21 which is herein shown as a refrigerant containing chamber is formed of a drawn sheet metal tube having one end thereof open which receives a ring 40 which is suitably sealed in position. A head or valve plate 42 is secured to the ring 40 by screws 43 and carries shut off valves 44 and 45 which are connected respectively with pipes 24 and 25. The head 42 is provided with an opening 47 communicating with the valve 45 and carries an inwardly extending and upwardly sloping tube 48 for conveying gaseous refrigerant from the free space above the liquid in the refrigerating chamber. The head 42 is also provided with a cylindrically shaped inwardly extending boss 50 having a screened opening 51 which communicates with the valve 44. The size of the opening 51 is reduced to a small orifice 53 which provides a seat for a needle valve 55. A sleeve 58 is secured to the boss 50 and is provided with an inwardly extending ledge 60 for supporting a float bracket 61 and a float 62. The support 60 is bifurcated at 65 to receive a portion of an actuator or lever 68 which actuates the valve 55, the valve being pivotally connected to the lever 68 at 69. The lever 68 is pivotally mounted between the forks of the support 60 by means of a pin 70 carried by the lever. The pin 70 extends through the support 60 to thus provide a pivotal mounting 72 for the float bracket 61 on opposite sides of said support. Thus it will be noted that the pin 70 provides a pivotal mounting for the actuator for the valve and a pivotal mounting for the bracket 61 which pivotally connects the float with the support.

Means is provided for yieldingly maintaining the float in a predetermined position with respect to the valve actuator during normal operation of the float. Thus the spring 80 may be provided, which spring may be, for instance, a helical spring. The spring 80 may have one end connected to the lever 68 and the other end to a flange 82 which forms a part of the bracket 61. 100

Means is provided for adjustably maintaining said float in a predetermined position with respect to the actuator during normal operation of the float. As shown in the drawings a screw 84 may be threaded into a flange 85 forming a part of the bracket 61. Thus it will be noted that the screw 84 engages the lever 68, and that said screw may be turned to vary the position of the float with respect to the lever 68. By varying the position of the float with respect to the lever 68, the operation of the valve 55 will be varied, as is well understood to those skilled in the art.

It will be apparent from the foregoing that the flow of refrigerant through the evaporator will be controlled by the needle valve 55 which controls the flow of refrigerant from receiver 31 and this flow is responsive to the float 62 so that when a predetermined quantity of refrigerant is contained in the chamber 21, the float will close or tend to close the needle valve and thus stop or impede the flow of refrigerant to the evaporator. For the purpose of illustration I have shown the refrigerant level at 86 and an oil level at 87.

The operation of the float mechanism is as follows. As the refrigerant in the chamber increases, the float will move upwardly and by means of the spring 80 said float will actuate the lever 68 which in turn tends to close the valve. As the refrigerant in the chamber 21 decreases, the float will move downwardly and by means of the screw 84 said float will actuate the lever which in turn tends to open the valve. In order to prevent the valve 55 from being removed too far from its seat, the valve actuator 68 is provided with a stop 90 which engages the support 60 when the actuator reaches a predetermined position.

In the event the mechanism including the float is subjected to abnormal conditions, such as severe shocks, as for instance, such shocks as may occur during transportation of the evaporator, the float 62 would be jarred upwardly very quickly and if it were not for the yieldable spring 80 said float would jam the needle valve 55 into its seat and thereby damage said valve or its seat, or both. Thus, when this abnormal condition occurs, the spring 80 will yield and permit the float to move upwardly beyond its normal operating position to thus prevent the float mechanism and actuator from jamming the needle valve into its seat since the direct thrust of the float upon the actuator and valve is thereby avoided. After the shocking or jarring of the float is over, the spring 80 will return the float 62 to its normal operating position with the screw 84 again engaging the lever 68.

While the form of embodiment of the invention as herein disclosed constitutes a pre-

ferred form, it is to be understood that other forms might be adopted, all coming within the scope of the claims which follow.

What is claimed is as follows:

1. In an evaporator for a refrigerating apparatus, the combination with a valve, of an actuator for said valve, a float, and connecting means for yieldingly maintaining said float in a predetermined position with respect to said actuator during normal operation of said float. 70

2. In an evaporator for a refrigerating apparatus, the combination with a valve, of an actuator for said valve, a float, and connecting means for resiliently maintaining said float in a predetermined position with respect to said actuator during normal operation of said float. 80

3. In an evaporator for a refrigerating apparatus, the combination with a container 85 having a restricted passage, of a valve for controlling said passage, a lever for actuating said valve, a float, and connecting means for yieldingly maintaining said float in a predetermined position with respect to said lever 90 during normal operation of said float, said means being adapted to yield during movement of the float in a predetermined direction in the event of abnormal operation of said float. 95

4. In an evaporator for a refrigerating apparatus, the combination with a valve, of an actuator for said valve, a float, and connecting means for adjustably maintaining said float in a predetermined position with respect to said actuator during normal operation of said float. 100

In testimony whereof I hereto affix my signature.

OTTO M. SUMMERS. 105
